UNITED STATES PATENT OFFICE.

JOHN W. DONNELL, OF ST. LOUIS, MISSOURI.

DESIGN FOR A BOTTLE.

SPECIFICATION forming part of Design No. 16,016, dated April 7, 1885.

Application filed February 2, 1885. Term of patent 7 years.

To all whom it may concern:

Be it known that I, JOHN W. DONNELL, a citizen of the United States, residing at St. Louis, in the State of Missouri, have invented and produced a new and original Design for Bottles, of which the following is a specification, reference being had to the accompanying drawings, forming part thereof.

Figure 1 is one half in side elevation and the other half in vertical section at 1 1, Fig. 2. Fig. 2 is a horizontal section at 2 2, Fig. 1.

The bottle has a flat bottom, *a*, from which the sides *b* extend up vertically to the shoulders *c*. The top of the bottle is horizontal in proximity to the neck *d*, or slightly inclined from the horizontal, as seen at *e*, the shoul-

ders *c* having a curve of a small radius, so as to give the bottle a general square appearance. The horizontal section of the bottle is an elongated ellipse, the transverse diameter, as shown, being over two and one-half times the conjugate diameter.

I claim—

The design for a bottle, consisting of a body, *b*, having flat bottom, horizontal top, vertical sides, and slightly-rounded corners, and of elongated elliptical form in cross-section, as shown and described.

JOHN W. DONNELL.
